UNITED STATES PATENT OFFICE.

ELIZABETH S. CANNON, OF ST. LOUIS, MISSOURI.

CHILD'S GARMENT.

1,125,467.

Specification of Letters Patent. Patented Jan. 19, 1915.

Application filed January 26, 1914. Serial No. 814,873.

To all whom it may concern:

Be it known that I, ELIZABETH S. CANNON, citizen of the United States, residing at St. Louis, State of Missouri, have invented certain new and useful Improvements in Children's Garments, of which the following is a specification, reference being had therein to the accompanying drawing.

This invention relates to children's garments of a character more particularly adapted to take the place of the usual coat or sweater and leggings, for use more especially in cold weather.

It has been before suggested to provide outer garments, more particularly sweaters and leggings, adapted to fit over the usual clothes of the child, but such prior garments of the character under consideration, with which I am familiar, have certain defects and objections, primarily because not altogether comfortable to the wearer, and the inclosed garments, such as the dress, would become rumpled, thereby presenting a very unseemly appearance after the removal of the outer garment.

Among the primary objects of the present invention, is the provision of an outer garment adapted to closely fit about the neck and limbs of the wearer, and to provide sufficient fullness about the hips and at the crotch to permit the inclosed garments to lie smooth about the wearer without becoming rumpled.

In carrying out the invention I preferably provide a body part for the garment having connected coat, leggings, and hood members, the leggings adapted to fit snugly about the ankles, the collar adapted to fit closely about the neck, and the body part constructed to provide the necessary fullness for absolute comfort to the user and protection for the inclosed garments against mousing.

It is still a further object of the invention to provide a child's outer garment of a character simple in construction, cheap to manufacture, pleasing in appearance, durable and efficient in use.

Other improvements and novel details in the construction and arrangements of parts

will be more particularly appreciated from the detailed description to follow, which for a clear understanding of the invention is to be considered in connection with the accompanying drawings forming a part hereof, 55 and wherein is disclosed a preferred and satisfactory embodiment of the invention.

In the drawings:—Figure 1 is a front view of the garment with certain parts in open position; Fig. 2 is a plan view of the 60 blank from which the body portion of the garment is formed; Fig. 3 is a plan view of the two blanks forming the hood.

With more particular reference to the drawings, like reference characters refer to 65 corresponding parts throughout the several views:

The body part of the garment is preferably made up as follows:—1 is a back portion, the opposite sides of which taper inwardly at 1^a toward the top thereof, and connected along the line 1^a are sides 2 the outer edges 2^a being also tapered inwardly toward the upper end. The sides 2 are preferably formed of the same piece of material 75 as the back 1 and are adapted to be folded along the lines 1^a whereby to form the front of the garment, and said parts 2 are of a width greater than half the width of the back whereby to provide fullness between 80 the front and back, and whereby the front sections 2 may overlie at their edge and be secured one to the other in any desired manner, as by fasteners 3. Auxiliary securing means, such as button and loop parts 4 may 85 be provided to add to the appearance of the garment at these points.

The lower portion of the body part of the garment is extended to form leggings, the back parts of the leggings being separated 90 from the front parts thereof by a substantially V-shaped cut out part 5 whereby when the front is folded upon the back, a close fit about the ankles at this point is insured, the adjacent edges of the front and back parts of the leggings at the cut out part being provided with securing means, such as fasteners, 6, of any improved type, so as to have the resemblance of ordinary leggings at this point. The lower edge 7 of the 100

back portion of the leggings has a cut out part 8, gradually curving inwardly, so as to provide an arch part 9 at the crotch. This is an important feature of the invention, since were the cut out part to take the form of a substantially inverted V-shape, the close fit at this point results in discomfiture to the user and makes necessary the folding and wrinkling of the under garments into the leg portions of the garment.

The front portion of the leggings, formed by the downward extensions of the sides 2 have at their lower outer edge, as shown in the blank, Fig. 2, a curved cut out part 10, adapted when the front portions 2 are folded over the back 1 to be stitched to the arch part 9 of the back to close the garment at this point. Suitable straps 11 may be provided to extend under the shoe of the user.

20 The arms 12 for the garment are preferably secured at the cut out portions 13 of the front and back parts, at their connecting upper edges. When the front parts of the garment are folded over the back, the front 25 is secured to the back, preferably by stitching, along the lines 14, the front and back portions having a curved central cut out portion 15 adapted for the reception of the neck of the user.

30 Secured to the neck portion of the garment is a suitable hood, the same preferably comprising two blanks 15^a, a detail of which being illustrated in Fig. 3, the said blanks being secured, one to the other as by stitching, along the upper edges 16 and rear edges 17, leaving a front opening at the part 18 for the face of the user. The sides of the hood have a substantially V-shaped cut out part 19, the edges of which are sewed to one another, whereas the rear edges of the blanks are cut away at 20, and sewed to one another, to the end that the hood will assume a snug fit at this point about the neck and head of the user. Also the hood is 40 provided with integral extensions 21, at the front thereof, of a length to overlap and be secured, as by fasteners 22, thereby providing a collar for the garment, as well as means for snugly fitting over the neck and under the chin to exclude air at this point. The collar portion of the hood is secured, at 23, as by stitching to the body part of the garment.

45 It is obvious, of course, that the sleeves may be provided with suitable cuff parts 24 and that the garment itself may be made of any warm material, such as chinchilla, and lined, if preferred, whereby to preserve the shape and prevent stretching.

The use of the garment is well understood from the above. In its application, the garment is open at its front, and the outer edge of the leggings is also opened. When applied over the ordinary house clothes of the child or infant, it will be seen that

considerable fullness is provided adjacent the lower portion of the body, around the hips, and at the crotch, thereby presenting a pleasing appearance as also a comfortable effect upon the user. This considerable 70 fullness at the points mentioned also permits of the dress and other under garments assuming a flat and smooth condition, to the end that when the outer garment is removed, the dresses and the like will be devoid of 75 the customary wrinkles due to folding the same about the legs of the wearer and into the leg portions of the leggings. This considerable fullness at the points mentioned is partly provided for by the tapering formation of the back and front parts and by the 80 particular form of arch-shape crotch here-tofore referred to. After being applied, the outer edges of the leggings are secured by the fasteners, whereby to tightly fit about 85 the ankles, and the front fastenings of the body part are united, and if desired, the hood applied over the head. The hood, at the front constitutes a collar for the garment, and even when not applied over the 90 head, the back portion of the hood will extend a considerable distance above the neck because of the close fitting character of the hood at this point, and thereby protect the neck of the wearer entirely therearound. 95

I claim:

1. In a combination coat and leggings garment for children, a body part having a back portion, the opposite sides of which taper outwardly from the top to a point below the hip part thereof, and thence inwardly toward the bottom of the leggings, and opposed front parts, one connected to each of said tapering sides of the back part, said front parts also increasing in width in 100 a downward direction from the top, said front parts being connected to the back part to form leggings, and means for fastening the free edges of the front parts of the garment to one another. 110

2. In a child's garment, a combined coat and leggings, the leggings being formed by an extension of the coat and combining therewith to provide fullness at and adjacent the hip portion, and said garment having a horizontally extended substantially arch-shaped crotch part. 115

3. In a child's garment, a combined coat, leggings and hood, the leggings being integral extensions of the coat part, and the 120 hood being secured at its lower edge to the upper edge of the coat and forming a collar for the coat, the said collar having extensions beyond the front edges of the hood adapted to be united under the chin of the 125 user.

4. In a child's garment a combination coat and leggings, the leggings forming an integral extension of the coat part, the outer edge of the leggings gradually tapering in- 130

wardly toward the foot portion thereof, and the front and back portions of the leggings being separated at said tapering edges, fastening means for said separated edges of the leggings, and the inner edges of the leggings gradually curving inwardly toward the top to form a substantially wide crotch part.

In testimony whereof I hereunto affix my signature in the presence of two witnesses.

ELIZABETH S. CANNON.
